UNITED STATES PATENT OFFICE.

PAUL A. GOELNICK, OF CHICAGO, ILLINOIS, ASSIGNOR TO SPIEGEL, MAY, STERN CO., OF CHICAGO, ILLINOIS, A CORPORATION OF ILLINOIS.

GUIDEWAY FOR CARDS AND THE LIKE.

Application filed October 22, 1924. Serial No. 745,115.

This invention relates to improved means for guiding cards, stencils and the like along a definite path. The improved guideway is particularly adapted for use in addressing machines wherein impressions are made from stencils which are automatically driven through a predetermined path to a printing position adjacent an inking roller which is controlled by a selector mechanism arranged 10 to coact with the stencils.

The main objects of this invention are to provide an improved form of guideway adapted to accommodate cards of various widths; to provide an addressing, tabulating and recording machine or the like having improved means for accurately guiding stencils and index cards along a definite path; to provide an improved form of guideway for addressing, tabulating and recording machines and the like adapted to accommodate cards and stencils of various sizes and to secure both stencils and cards against any lateral shifting or variation from the fixed path along which they are moved; to provide a device of this kind having an improved form and arrangement of resilient elements for urging the stencils and cards against one rail of the guideway; and to provide an improved mounting for 20 the resilient elements whereby a broken element may be readily removed and replaced without disturbing the positions of the other elements.

An illustrative embodiment of this invention is shown in the accompanying drawings, wherein—

Figure 1 is a plan of the improved guideway, partly broken away for the sake of clearness, and showing also part of the horizontal supporting table of an addressing machine.

Fig. 2 is a front elevation of the guideway showing also part of a selector mechanism and hopper.

Figs. 3 and 4 are details in elevation of an index card and stencil respectively.

Fig. 5 is an enlarged detail in section of the front guide rail, the view being taken on the line 5—5 of Fig. 7.

Fig. 6 is an enlarged transverse section of the guideway and part of the selector mechanism, the view being taken on the line 6—6 of Fig. 1.

Fig. 7 is a detail of part of the front guide rail, showing the normal position of each

bow spring, and also showing in dotted outline the position to which the spring is shifted when it is desired to withdraw it from the rail.

Fig. 8 is a detail of the front guide rail, 60 showing the position of the bow spring at the beginning of its rocking movement when placed under tension by engaging the forward edge of the stencil.

Fig. 9 is a similar view showing the position of the bow spring at the middle of its rocking movement.

Fig. 10 is a similar view showing the position of the bow spring at the end of its 70 rocking movement.

The common form of addressing machine to which this invention may be applied, comprises a horizontal guideway along which the stencils are moved to a printing position beneath an inking roller, which is controlled 75 in its operation by a selector mechanism arranged directly above a portion of the guideway. The selector mechanism coacts with the stencils for controlling one or more electric circuits, which operate the printing 80 roller and certain other parts of the machine. The stencils and index cards are usually stacked together in the hopper of the addressing machine, from which they are fed by gravity to the guideway. Heretofore the 85 stencils and index cards have been of similar size, and, therefore, it has been necessary to recess the stencils along the upper edges thereof so as to provide openings 90 through which the indexes have been visible 95 when the stencils are filed vertically.

In the specific construction herein shown, the present invention contemplates the use of index cards of greater height than the stencil so that the indexes are visible above 95 the stencils. Inasmuch as the present invention relates particularly to the guideway, only that part of an addressing machine which is believed necessary to a complete 100 understanding of the invention has been illustrated in the accompanying drawings.

In the form shown, the addressing machine to which this invention is applied comprises a stationary frame 1, having a horizontal table 2, on which is mounted an upright hopper 3, from which stencils 4 and index cards 5 are automatically fed in a step by step movement along an improved 105 guideway 6. Suitable feeding mechanism, not shown, is arranged adjacent the hopper 110

3 for moving the stencils along the guideway 6 to the printing mechanism, which is controlled by a selector mechanism 7. The printing roller and other parts of the machine controlled by the selector mechanism are not shown in the drawings.

The stencils 4 may be of the common form comprising a thin membrane 8, wherein the characters are cut, and which is mounted in 10 a rectangular card-board frame 9. Formed in the stencil frame 9, are one or more apertures 10, adapted to receive the pins 11 of the selector mechanism 7. The position of the apertures 10 on the frame 9 determines the selection, as is well understood and more fully described in the co-pending application of Paul A. Gollnick and John J. Toolan, Serial No. 718,087, filed June 5, 1924, relating to selector mechanisms for 20 addressing machines.

The index cards 5 may be of card-board or other suitable stiff material, having each a body portion of substantially the same size as the stencils 4, and having a top portion 25 12 at the upper edge thereof which projects above the stencils 4 when the stencils and cards are filed vertically in the usual trays or drawers, so that the indexes are visible above the stencils. A convenient form of 30 index card is shown in Fig. 3.

In the specific form herein shown, the improved guideway 6 comprises a pair of rails 13 and 14, mounted on the horizontal table 2, and disposed in substantially parallel 35 spaced relation. The back rail 13 may be in one piece, which is recessed along its inner edge to form a longitudinally extending groove 15 for receiving the rear edges of the stencils and cards. The front rail 14 preferably comprises two plates 16, which are spaced apart vertically to form a guideway between them for receiving the forward edges of the stencils and cards. Formed in 40 the rails 13 and 14 adjacent the inner edges thereof, are apertures 6.1 arranged to receive the selector pins 11 for guiding them into the apertures 10 of the stencils.

In addressing machines it is essential that the stencils be moved along a definite path 50 without any variation therefrom, so as to permit the selector pins 11 to accurately contact with the apertures 10 of the stencils. In the device herein shown, the stencils and cards are secured against lateral shifting 55 or any variation from their true path by means of a plurality of resilient elements 17, located between the guide plates 16 of the rail 14, and which are arranged to urge the stencils and cards against the rear guide 60 rail 13, as shown in Figs. 1 and 6.

In the specific form herein shown, the resilient elements 17 comprise bow springs having the bights thereof projecting inwardly into position to engage the forward 65 edges of the stencils 4 and cards 5. The

ends of the springs 17 are curved so as to partially embrace pins 18, which are mounted in the guide plates 16 adjacent the outer edge thereof. The pins 18 form fulcrums around which the bow springs are adapted to rock under the action of cards passing through the guideway as shown in Figs. 70 8, 9 and 10. When the forward part of a card engages the bow spring, as shown in Fig. 8, the outer end of the spring is forced 75 away from its pin 18, and as the card rides along the spring the looped end thereof is forced outwardly while the outer end again moves into engagement with the adjacent pin 18. This improved rocking motion of 80 the springs tends to prevent an abrupt bending of the spring at any one point and thus lengthens the life of the springs. The springs 17 are locked to the rail 14 by removable pins or screws 19, mounted on the 85 plates 16 and extending through the bight of each spring, as illustrated in Figs. 7, 8 and 9. With this improved construction, any of the springs 17 may be readily withdrawn and replaced without disturbing the 90 other springs. To remove a spring from the rail 14, after the respective pin 19 has been withdrawn, it is shifted into the position shown in dotted outline in Fig. 7, and is then pulled outwardly between the two fixed 95 pins 18. A sufficient number of springs 17 are used to insure contact of the stencils 4 and cards 5 with the rear rail 13. As shown in Fig. 1, two springs 17 are arranged adjacent the selector mechanism so as to firmly 100 hold the stencil which is being acted upon by the selector pins 11.

Located between the springs 17, are filler blocks 20, to which the guide plates 16 are rigidly secured by screws 21 or other suitable fastening means. The end block 20, adjacent the hopper 3, is recessed at its outer edge to form a shoulder 22, which takes the place of one of the pins 18 for retaining the end of the spring 17.

In operation, the stencils and index cards are moved in a step by step motion along the guideway 6 so as to be brought in succession to a position directly below the selector pins 11. During the movement of 110 the stencils and cards through the guideway 6, their outer edges engage the bow springs 17, which are thereby placed under tension, as shown in Figs. 8 and 9, for urging the stencils and cards against the rear rail 13. 120

Although but one specific embodiment of this invention has been herein shown and described it will be understood that numerous details of the construction shown may be altered or omitted without departing 125 from the spirit of this invention as defined by the following claims.

I claim:

1. A device of the class described comprising a guideway for receiving a row of 130

cards arranged edge to edge and movable through a predetermined straight path, one of the lateral edges of said guideway having a resilient part in position to directly engage the cards for urging them against the opposite lateral edge thereof during their travel along said guideway.

5 2. A device of the class described comprising a guideway having substantially parallel lateral edges between which cards of various widths are movable edge to edge through a predetermined straight path, and a spring mounted on said guideway and projecting inwardly from one of said lateral edges into position to directly engage the cards for urging them against the opposite lateral edge during their travel along said guideway.

10 3. A device of the class described comprising a guideway having a pair of substantially parallel rails for receiving cards movable edge to edge through a predetermined straight path, and a plurality of separate and detachable bow springs projecting inwardly from one of said rails into position to directly engage the cards for urging them against the opposite rail.

15 4. A device of the class described comprising a guideway having a pair of substantially parallel rails for receiving cards, one of said rails having an opening extending transversely therethrough, and a resilient element mounted in said opening and pro-

jecting beyond the inner edge of said one rail so as to be adapted to engage the cards 35 for urging them against the opposite rail.

5 5. A device of the class described comprising a guideway having a pair of substantially parallel rails for receiving cards, one of said rails having an opening extending 40 transversely therethrough, a spring arranged in said opening and projecting inwardly beyond the inner edge of said one rail for engagement with the cards to urge them against the opposite rail, and means detachably securing said spring to said one rail, said spring being adapted to be withdrawn through the outer end of said opening upon the release of said means.

10 6. A device of the class described comprising a guideway having a pair of substantially parallel rails for receiving cards, one of said rails having an opening extending 45 transversely therethrough, a bow spring arranged in said opening with a portion thereof projecting inwardly into position to engage the cards for urging them against the opposite rail, retaining parts on said one rail coacting with the ends of said spring, and a removable pin arranged in said opening and located within the bight of said bow spring for locking said spring to said one rail.

Signed at Chicago this 26th day of Sept., 1924.

PAUL A. GOLNICK.
